ASH TRAY

Marianne Tuteur, New York, N. Y., assignor to Talon, Inc., a corporation of Pennsylvania

Application June 13, 1952, Serial No. 20,172

Term of patent 7 years

(Cl. D85—2)

To all whom it may concern:

Be it known that I, Marianne Tuteur, a citizen of the United States, residing at New York, in the county and State of New York, have invented a new, original, and ornamental Design for an Ash Tray, of which the following is a specification, reference being had to the accompanying drawing, forming a part thereof.

In the drawings:

Fig. 1 is a perspective view of an ash tray, showing my new design;

Fig. 2 is a side elevational view thereof;

Fig. 3 is a rear elevational view thereof;

Fig. 4 is a front elevational view thereof; and

Fig. 5 is a sectional view taken on line 5—5 of Fig. 1.

I claim:

The ornamental design for an ash tray, substantially as shown.

MARIANNE TUTEUR.
